(57) **CLAIM**

The ornamental design for the motion sensor, as shown and described.

DESCRIPTION

FIG. 1 is a front, right and top perspective view of the motion sensor with a mount shown as environment in broken lines; FIG. 2 shows a rear, left, and bottom perspective view of the motion sensor with a mount shown as environment in broken lines; FIG. 3 shows a rear, left, and bottom perspective view of the motion sensor; FIG. 4 shows a front plan view of the motion sensor; FIG. 5 shows a rear plan view of the motion sensor with a mount shown as environment in broken lines; FIG. 6 shows a right side elevation view of the motion sensor with a mount shown as environment in broken lines, the left side elevation view of the motion sensor being a mirror image thereof; FIG. 7 shows a top plan view of the motion sensor with a mount shown as environment in broken lines; and, FIG. 8 shows a bottom view of the motion sensor with a mount shown as environment in broken lines.

The broken lines present in FIGS. 1, 2, 5, 6, 7 & 8 illustrate environment of the motion sensor that forms no part of the claimed design.
